UNITED STATES PATENT OFFICE.

TARGE G. MANDT, OF STOUGHTON, WISCONSIN.

BOX-FASTENER.

SPECIFICATION forming part of Letters Patent No. 695,409, dated March 11, 1902.

Application filed November 6, 1901. Serial No. 81,336. (No model.)

To all whom it may concern:

Be it known that I, TARGE G. MANDT, a citizen of the United States, residing at Stoughton, in the county of Dane and State of Wisconsin, have invented new and useful Improvements in Box-Fasteners, of which the following is a specification.

My invention relates to box-fasteners; and the object of the same is to construct a device adapted to be used on beer-cases and which will not be liable to be deranged in handling the cases. The simple and novel construction by which this object is accomplished is fully described in this specification and claimed, and illustrated in the accompanying drawings, forming a part thereof, in which—

Figure 1 is a side elevation of my box with parts broken away. Fig. 2 is a bottom plan of the cover. Fig. 3 is a detail of the crank-shaft and lever. Fig. 4 is a detail of the catch.

Like numerals of reference designate like parts in the different views of the drawings.

The numeral 1 designates a box having sides 2 and ends 3. A cover 4 is provided for the box, which cover bears transverse parallel cleats 5, secured to the under side and located to abut the sides 2 and fit against the ends 3 when the cover is in place. A pair of hangers 6 are attached to the under side of the cover 4 intermediate the cleats 5, which hangers serve to support a crank-shaft 7, journaled in apertures 6^a therein. The shaft 7 is provided with two pair of oppositely-extending cranks 8 and a lever-arm 9. Attached to the cranks 8 by eyes 10^a are four locking-bolts 10, mounted to slide in transverse apertures 5^a in the cleats 5, which serve as guides. The bolts 10 each have beveled points 10^b, constructed to engage the ends 3 of the box. The lever 9 is curved and extends through a slot 11 in the lid 4, so as to enable it to be operated from the outside. When down, the lever fits in the slot 11 below the surface of the lid, and is therefore not liable to be displaced in handling the box. Rounded lugs 9^a, formed on the lever 9, engage recesses 11^a in the lid, and thereby limit the downward swing of the lever 9. A spring-catch 12, having a rounded head 12^a, engages one side of the slot 11 and serves to prevent the accidental displacement of the lever, but enables it to be

raised by the application of force. An aperture 13 at the end of the slot 12 enables the end of the lever to be readily grasped by the fingers to disengage the catch. The curve of the lever 9 is such that when it is lying in the groove 13 the cranks 8 are extending parallel to the lid.

In putting the lid on the box the lever is first raised to retract the bolts, after which the lid is placed in position. The lever is then forced down and the bolts 10 operated, thereby bringing their sharpened ends into engagement with the ends of the box. It should be noted that the bolts are beveled on the upper sides, which causes the cover to be drawn down as the beveled ends of the bolts are forced into the wood.

I do not wish to be limited as to details of construction, as these may be modified in many particulars without departing from the spirit of my invention.

Having described my invention, what I claim as new, and wish to secure by Letters Patent, is—

1. The combination with a box of a cover for said box constructed to fit over the edges of the same, a shaft mounted on the under side of said cover and having oppositely-extending cranks, a lever for operating said shaft, means for locking said lever against accidental displacement, bolts connected to said cranks and having sharpened ends beveled on their upper sides to adapt them to engage the box ends to draw the cover down when the lever is operated, and guides for said bolts, substantially as described.

2. The combination with a box of a cover for said box constructed to fit over the edges of the same, transverse cleats on the under side of said cover, a shaft having oppositely-extending cranks, a lever for operating said shaft, means for securing said lever against accidental displacement, bolts connected to said cranks and mounted to slide in apertures in said cleats, said bolts having sharpened ends beveled on their upper sides to adapt them to draw the cover down to snugly fit said box, substantially as described.

3. The combination with a box-cover, having a slot therein, of a crank-shaft mounted on the under side of said cover, and having a lever extending through said slot and pro-

vided with a catch located to engage the edge of said slot, and sliding bolts connected to said cranks and constructed to secure the cover on a box, substantially as described.

- 5 4. The combination with a box-cover, having a slot therein, of a crank mounted on the under side of said cover and bearing a lever extending through said slot and provided with a catch located to engage the edge of the slot
10 and lugs located to engage the lid to limit the movement of the lever, and sliding bolts con-

nected to said cranks and constructed to secure the cover on a box, substantially as described.

In testimony whereof I have hereunto set my hand in presence of two subscribing witnesses.

TARGE G. MANDT.
